UNITED STATES PATENT OFFICE.

HIRAM C. ANDERSON, OF WESTCHESTER, NEW YORK, AND JAMES GAFFNEY, OF ROSELLE, NEW JERSEY.

MUSIC-SHEET TURNER.

1,156,199.

Specification of Letters Patent.

Patented Oct. 12, 1915.

Application filed October 9, 1914. Serial No. 865,901.

To all whom it may concern:

Be it known that we, HIRAM C. ANDERSON, citizen of the United States, residing at Westchester, in the county of Bronx and State of New York, and JAMES GAFFNEY, citizen of the United States, residing at Roselle, in the county of Union and State of New Jersey, have invented certain new and useful Improvements in Music-Sheet Turners, of which the following is a specification, reference being had to the accompanying drawings.

This invention relates to an improved music sheet turner, and has for its primary object to provide a simple, inexpensive, and reliable device of this character for turning the sheets of music.

The invention has for another very important object to provide a device of the above character which is so constructed that the same may be readily mounted or arranged upon a music stand, the music desk of a piano, or in a sheet music folio.

It is a further object of our invention to provide a device for the above purpose which may be operated with ease and facility and is of great convenience and serviceability in practical use.

With the above and other objects in view, our invention consists in the novel features of construction, combination, and arrangement of parts to be hereinafter more fully described, claimed, and illustrated in the accompanying drawing, in which,

Figure 1 is a plan view showing the subject matter of our invention applied to a folio such as is commonly used for carrying sheet music, and the music sheets properly attached to the turning arms; Fig. 2 is an enlarged elevation showing the mounting of the supplementary sheet turning arms, and one of said arms thrown over into the position it occupies after the sheet held thereby has been turned; Fig. 3 is an enlarged detail perspective view of one of the sheet turning arms; and Fig. 4 is a plan view showing the device mounted upon a single rigid base and the additional turning arms removed. Fig. 5 is a detail fragmentary perspective view.

Referring in detail to the drawing, 5 designates the backing strip of the folio which may be constructed of heavy cardboard, fiber, or other suitable material in the manner of the ordinary book. To the opposite

longitudinal edges of this backing strip, the foldable sides 6 of the folio are hingedly connected by means of the usual cloth binding sheet. To the strip 5 spaced bearing eyes or brackets indicated at 7 are secured, and in these bearings the longitudinally extending rod 8 is rotatably mounted. The lower end of this rod is laterally extended as at 9 to provide a suitable handle while the other or upper end thereof is also horizontally disposed to provide the sheet turning arm 10. The extremity of this arm is angularly bent and equipped with a suitable clamping device indicated at 11 for engagement with the upper edge of the music sheet. Additional or supplementary sheet turning arms shown at 12 are preferably each formed from a single wire rod, one of its ends being formed with an eye 13 loosely engaged upon a reduced portion of the rod 8 to turn with respect thereto. In this rod, adjacent to the eye 13, a smaller eye or loop 14 is formed which projects from the rod in a plane at right angles to the eye 13. The other end of the wire rod is angularly bent as at 15 and then returned or coiled to provide a clamping loop 16 upon its extremity.

Upon the inner face of the front side wall 6 of the folio and adjacent to the longitudinal edge thereof, a guide eye 17 is secured through which a link chain 18 extends. One end of this chain is provided with a ring 19 which is engaged in the eye 14 of one of the sheet turning arms 12. The chain 18 is also provided with a second eye 20 loosely engaged upon the other of the wire arms 12 and outwardly of the loop 14 therein. It will be noted that when both of the arms 12 are disposed on the right hand side of the rod 8, there is considerable slack in the chain 18 between the eyes 19 and 20.

Suitable brackets 21 are secured to the front and back side walls 6 of the folio upon which the lower edges of the music sheets are adapted to rest. It will be understood that these brackets are so located with respect to each other that they will not contact or in any way interfere with the proper closing of the folio. After the first sheet of music has been opened upon the front wall 6 of the folio, the next sheet is engaged at its upper edge in the clamp 11 provided on the arm 10 of the rod 8. The next music sheet is engaged by the clamping loop 16 on the end of the wire arm 12 upon which the ring 17

20 of the chain 18 is engaged. It will be understood that the edge of the sheet is disposed upon the downwardly extended end portion 15 of the arm, the loop 16 formed thereon being sprung upwardly and engaged upon the upper face of the sheet. The other of the music sheets is then attached in a similar manner to the second arm 12 to which the end of the chain is permanently secured and which lies directly upon the back wall 6 of the folio. Having secured the sheets to the turning arms in this manner, when the musician desires to turn the second sheet of music, the lower end 9 of the rod 8 is swung over to the left upon the front wall 6 of the folio, thus also swinging the arm 10 upon the upper end of said rod and turning the sheet which is carried thereby. To turn the next sheet, the operator pulls upon the end of the chain 18. The ring 20 of said chain engages against the loop 14 of the rod 12 which acts as a stop, thus causing the chain to exert a pull upon the turning arm to swing the same on the rod 8 whereby the music sheet is turned over. In order to turn the next sheet, the chain is given a further pull so that the ring 20 will slide outwardly upon the arm 12 which has been turned while the other arm 12 to which the end of the chain is attached, is turned upon the rod 8, thus swinging the same thereon and turning the sheet. In this manner, the several sheets of music may be successively turned. To repeat the music, all of the sheets may be turned together to the right, by simply swinging the handle 9 on the lower end of the rod 8 over upon the back wall 6 of the folio. The back wall of the folio is provided with a suitable handle 22 on its longitudinal edge and also fastening straps indicated at 23. In view of the very few parts employed in the construction of the device, it will be apparent that the same will not interfere with the folding of the folio walls to their closed positions.

In Fig. 4 of the drawing, we have illustrated the device as applied to a single rigid base 24 which may be suitably mounted upon a music stand or other structure. In this mounting of the device, only the rod 8 is shown arranged to turn upon the board 24, said rod being centrally disposed thereon. It will be understood that when the music contains only a single loose sheet, it is not necessary to use the additional arms 12, and in Fig. 4 the device is shown employed in this manner. The construction and operation of the device is the same as that above referred to. It will also be manifest from the above disclosures, that the device may be readily mounted upon the music desk of a piano without detracting from the appearance thereof. The operator, by means of our invention, may very easily and quickly turn the music sheets. Any desired number

of the additional rods or arms 12 may be utilized in accordance with the general character of the music usually provided for the performer, but in the interests of clear illustration, such additional arms are not shown.

From the foregoing, the construction, manner of operation, and several advantages of our invention will be clearly and fully understood. The great convenience and serviceability thereof will be obvious. In view of the extreme simplicity of the invention, it will further be apparent that the same can be produced at very small manufacturing cost. It is also very durable in practical use.

While we have shown and described the preferred construction and arrangement of the several elements employed, it is to be understood that the device is susceptible of considerable modification therein, and we therefore reserve the privilege of resorting to all such legitimate changes as may be fairly embodied within the spirit and scope of the invention as claimed.

Having thus fully described our invention, what we desire to claim and secure by Letters Patent is:—

1. In a sheet turning device, a rod, turning arms loosely mounted at one of their ends upon said rod and provided upon their other ends with sheet clamping means, a flexible element connected at spaced points in its length to the respective turning arms and adjacent to said rod, whereby the arms may be successively swung upon the rod to turn the respective sheets by a series of pulls upon the flexible element.

2. In a sheet turning device, a rotatably mounted rod having a turning arm on one end provided with means for attaching a sheet thereto, additional turning arms loosely mounted at one of their ends upon said rod and also each provided with sheet clamping means, and manually operable flexible means permanently connected directly to each of said additional arms to independently operate the same and successively turn the sheets held thereby.

3. In a sheet turning device, a rotatably mounted rod having a turning arm on one end provided with means for attaching a sheet thereto, additional turning arms loosely mounted at one of their ends upon said rod and also each provided with sheet clamping means, a flexible element attached at one of its ends to one of said additional arms and slidably connected to the other of said arms, said latter arm being provided with a stop to limit the movement of said element with respect thereto in one direction, whereby said arm is first actuated when the flexible element is pulled to turn the sheet held thereby, the sheet held by the other arm being turned by a further pull of said element.

4. In a sheet turning device, a rotatable mounted rod having a turning arm on one end provided with means for attaching a sheet thereto, additional turning arms 5 loosely mounted at one of their ends upon said rod and also each provided with sheet clamping means, each of said arms being provided with an eye intermediate of its ends, a chain connected to one of said eyes, 10 and a ring carried by said chain and slidably engaged upon the other of the additional arms, the eye in said arm limiting the sliding movement of the ring thereon in one

direction, whereby when the chain is pulled said arm is first actuated to turn the sheet 15 held thereby, the sheet held by the other arm to which the chain is connected being turned by a further pull of said chain.

In testimony whereof we hereunto affix our signatures in the presence of two witnesses.

HIRAM C. ANDERSON.
JAMES GAFFNEY.
